UNITED STATES PATENT OFFICE.

EDWARD H. WALSH, OF CHICAGO, ILLINOIS.

MAGNETIC GRIP.

1,195,630.

Specification of Letters Patent. Patented Aug. 22, 1916.

Application filed March 29, 1916. Serial No. 87,458.

To all whom it may concern:

Be it known that I, EDWARD H. WALSH, a citizen of the United States, and resident of Chicago, in the county of Cook and State of Illinois, have invented certain new and useful Improvements in Magnetic Grips, of which the following is a specification.

My invention relates to shearing, punching and stamping machines and has particular reference to a novel gripping or holding device for use in connection therewith.

In the employment of shears, it is well known that the material to be sheared must be rigidly held or clamped during the shearing operation. If this is not done, the material will move laterally and a curved or helical cut will result. To obviate this and at the same time to facilitate production it is common to provide three or more workmen charged with the duty of retaining the plate or bar in its proper position during the shearing operation. The reason this facilitates production is that the shearing could not be conducted with rapidity if a mechanical clamp was to be adjusted at each operation.

I have conceived the idea of providing a clamp or hold-down device which operates automatically and with rapidity and eliminates the workmen heretofore required for such holding operation. By the use of my device it is only essential to provide such workmen as are necessary to properly dispose the article upon the bed, whereupon the shear or press is actuated and the article is automatically gripped during the shearing operation. The result is secured by providing a plurality of magnets or magnetic gripping devices located below the surface of the bed and connected to a source of electric energy, the means of connection being in the form of an automatic switch associated with the main shaft of the shear and which switch is actuated or completes a cycle of its movement during each revolution of the power shaft.

The invention will be more readily understood by reference to the accompanying drawings wherein,

Figure 1 is an end elevation of a power shear equipped with my invention; Fig. 2 is a front elevation of the shear; Fig. 3 is a plan view of the bed; Fig. 4 is a sectional view through the bed considerably enlarged

over that of Fig. 3, and, Fig. 5 is a wiring diagram.

In the drawings I have illustrated the invention as applied to a shear of the vertically reciprocating type. This device may include frame members 10, a bed 11, to which the lower shear knife 12, is rigidly secured. Mounted within the frame is the main power shaft 13, on which the eccentrics 14, 14, are secured. The reciprocation of the upper shear blade 15, is brought about by the eccentrics in a manner well understood.

Mounted in the bed 11, are the magnets, the method of mounting being shown in Fig. 4. These magnets comprise a core 16, screw-threaded into the base, the core being surrounded by the windings 17, the surface of the core being made flush and the windings retained in place by means of the plates 18. I have shown a relatively large number of these magnets in the bed, fourteen thereof being indicated in Figs. 3 and 5. Inasmuch as these cannot be properly carried all in series, I have divided them into two units and connected these units in multiple as best shown in Fig. 5. In that figure the supply and return wires are indicated at 19, 20, respectively. The magnets are indicated at 21, 22, while the terminals adapted to be connected by the switches are indicated at 23, 24.

The switches which I prefer to employ are best shown in Fig. 1, and where the magnets are divided into two sections I provide a switch upon each end of the machine, the movable element of the switch being in the form of a segment 25, secured to the end of the main shaft by means of the screws or bolts 26. The terminals 23, 24, are disposed in the path of the disk and as the segment makes one complete revolution at each actuation of the shear blade it will be seen that the magnetic devices are operated or are energized during substantially one half of each cycle of operation of the shear. The portion of the stroke of the shear during which the magnets are energized is of course the active portion or that portion during which the shearing operation takes place.

The operation of the device is as follows: Assuming that the shear is in the position of Figs. 1 and 2, a plate or bar to be sheared is located on the bed 11, in proper position be-

neath the shear blade 15. The mechanism is then actuated which starts the shear into operation. As the shaft 13, begins to revolve the segment 25, rotates therewith and the terminals 23, 24, are closed thus energizing the magnets. This serves to securely grip or hold the article, the holding action continuing until the shear has retracted and is substantially out of contact with the article.

It will be seen that the device as suggested is entirely automatic in its action, requires no attention or manual operation and may be installed at a very slight expense. Obviously modifications may be made in the construction as shown and such modifications as are within the scope of my claims I consider within the spirit of my invention.

I claim—

20 1. In a device of the class described, the combination of a bed and a movable element, a plurality of series of magnetic devices in said bed, a source of electric energy and a pair of switches connected to the main shaft 25 of said reciprocating element for actuating

said magnetic devices during a portion only of the stroke of said shaft, substantially as described.

2. In a device of the class described, the combination of a bed and a vertically reciprocating machine element, a shaft for operating said element, a plurality of magnets mounted in said bed and a switch carried by the end of said shaft and arranged to energize said magnets once during each revolution of said shaft, substantially as described.

3. In a device of the class described, the combination of a bed, a plurality of magnets mounted in said bed, a reciprocating element mounted above said bed, an eccentric shaft for actuating said reciprocating element and a segmental switch member carried by said shaft and so arranged that said magnets are energized during a portion only of the rotation of said shaft, substantially as described.

EDWARD H. WALSH.
